UNITED STATES PATENT OFFICE.

WALDO FRANK PEREZ, OF KEY WEST, FLORIDA.

BOTTLE-CAP.

1,114,181.

Specification of Letters Patent.

Patented Oct. 20, 1914.

Application filed November 2, 1911. Serial No. 658,255.

To all whom it may concern:

Be it known that I, WALDO F. PEREZ, citizen of the United States, residing at Key West, in the county of Monroe and State of Florida, have invented certain new and useful Improvements in Bottle-Caps, of which the following is a specification.

This invention relates to bottle caps and more particularly to that type designed primarily for use in sealing bottles containing beer and other carbonated beverages. The invention contemplates providing such a cap with a tongue or finger-piece which may be grasped and manipulated as a lever to pry off the cap from the bottle, and while it has before been proposed to provide a cap of this type with such a tongue, such prior devices present certain disadvantages which render them commercially impracticable, and which disadvantages the device of the present invention is designed to overcome. For example, as far as I am cognizant of the prior art, all such devices are so constructed that the finger-pieces or the tongues thereof lie against or extend beside the necks of the bottles to which they are applied and therefore requiring the insertion of an instrument of some sort between the tongue and the neck of the bottle, such instrument being employed as a lever to force the tongue outwardly from the neck and in this manner disengage the cap from the bottle. Chief among the disadvantages of such a construction is that the finger alone cannot be employed in removing the cap, or if it is employed, is liable to injury, and if an implement of any sort is inserted between the tongue of such a cap and the neck of the bottle to which it is applied, and is used as a lever to pry the cap from the bottle, the neck of the bottle is extremely liable to be fractured. A further disadvantage of such a structure resides in the fact that while the tongue of such a cap is designed to serve the purpose of a lever in prying the cap from the bottle, its direction of extent from the cap proper is such that it possesses little advantage or function to this end. To overcome the disadvantages above mentioned, and presented by a cap constructed as before briefly described, the present invention contemplates providing a cap of this type with a tongue or finger-piece which extends substantially at right angles from the bottle neck so that the maximum leverage is secured, as one advantage gained, and the

tongue may be readily grasped for the purpose of removing the cap and may be manipulated for this purpose without the employment of an instrument of any kind. 60 Such caps of this type as constitute the prior art usually have stamped up in the tongue or finger piece, a reinforcing rib, the purpose of which is to prevent bending of the tongue when the tongue is manipulated to pry off the cap, but such ribs as previously formed, have either been terminated short of the point of juncture of the tongue with the rim of the cap, or, have been extended into the rim in such member as to suitably reinforce 65 70 the tongue, but on the other hand to render the cap practically useless for the purpose of retaining the gas within the bottle.

The invention therefore, has for a further object to provide a cap of this type, the tongue of which is formed with a reinforcing rib so stamped therein as to form a continuation of one of the ribs occurring between two of the crimps in the rim of the cap so that the crimps in the rim extend in 80 an uninterrupted series in the same manner as they do in the common form of cap now in general use, although the tongue is so reinforced both throughout its entire length and also at its point of juncture with the rim of the cap, that it will not be liable to bend at said point of juncture or at any point in its length when manipulated to remove the cap from the bottle. 85

While it is above stated that the advantage gained by having the tongue extend from the cap so as to lie substantially at right angles to the neck of the bottle to which the cap is applied, is that the tongue may be readily grasped between the fingers 90 95 and, without the employment of an implement of any sort, and be readily manipulated to remove the cap, this arrangement of the tongue presents this further advantage:—A bar tender in opening a number 100 of bottles of beer will grasp a bottle in each hand and insert the necks of the bottles into an opener device fixed upon the bar, and while some little time is saved by grasping a bottle in each hand, it is necessary to successively insert the necks of the bottles. A bar-tender, on the other hand, handling bottles sealed by caps embodying the present invention, could readily grasp the necks of 110 two bottles in each hand and with the tongues of the caps projecting away from him and strike these tongues against the

edge of the bar, thereby practically simultaneously opening four bottles at one operation. Obviously this could not be done by the use of caps constructed with their 5 tongues designed to lie against or extend beside the necks of the bottles to which they were applied, and in fact whatever advantages such a construction of cap would have when adopted merely for private or family 10 use would be nullified if adopted for use by dispensers of such beverages, for the reason that it would require more time to remove a cap so constructed and with its tongue so positioned than it would to make use of 15 the ordinary opener in removing the common type of cap now in general use.

For a full understanding of the invention reference is to be had to the following description and accompanying drawing, 20 in which:

Figure 1 is a perspective view of a cap embodying the present invention. Fig. 2 is a side elevation thereof. Fig. 3 is a similar view but looking directly at the end of 25 the tongue of the cap. Fig. 4 is a vertical transverse sectional view on the line 4—4 of Fig. 2.

Corresponding and like parts are referred to in the following description and indicated in all the views of the accompanying drawing by the same reference characters.

In the drawing, the cap is illustrated as including the usual crown portion 1, which is flat or substantially flat and from which 35 depends the circumscribing rim 2, there being the usual cork or composition disk 3 positioned within the cap against the under side of the crown 1 for the purpose of preventing the escape of gas from the bottle 40 to which the cap is applied. As is usual, the rim 2 is formed with a series of crimps 4 extending continuously therearound, and it will be observed from inspection of the several figures of the drawing that this series 45 of crimps is at no point interrupted. The formation of the crimps 4 results in the formation, between them of short outstanding ribs or corrugations 5.

The cap of the present invention includes 50 a tongue which, aside from a reinforcing rib stamped therein, and to be presently specifically described, is flat, this tongue being indicated by the numeral 6. The reinforcing rib stamped up in the tongue 6 and above referred to, is indicated by the numeral 7 and by referring to the drawing, it will be observed that this rib forms and constitutes a continuation of one of the ribs 5 occurring between two of the crimps 4. 55 In other words, one of the ribs 5 and the reinforcing rib 7 intermerge at the point of juncture of the tongue with the rim of the cap, so that the rib 7 will extend into the said rim of the cap.

60 From inspection of Fig. 1 of the draw-

ing it will be observed that the tongue 6 has its lateral edges converging in the direction of its outer end, and that the said lateral edges at their inner ends merge with the rim of the cap at points at the middles of the lower edges of the crimps between which is located that rib 5 of which the reinforcing rib of the tongue forms a continuation. It will further be observed by referring to Figs. 2 and 3 of the drawing that the under side of the tongue 6 lies in a horizontal plane parallel to the plane of the crown portion 1 of the cap and that the upper side or edge, so to speak, of the reinforcing rib, is inclined downwardly and outwardly in a direction from the plane of the crown portion 1 toward the plane of the under side of the tongue 6.

From the foregoing description of the invention it will be readily understood that the crimps in the rim of the cap extend in a continuous and uninterrupted series around the rim of the cap in exactly the same manner as do the crimps in the rim of that type of cap now in common use; so that the cap of the present invention will obviously seal a bottle to which it is applied as effectually and in the same air tight manner as does the old type of cap. It will further be observed that the tongue projects laterally from the rim of the cap and, when the cap is applied to a bottle, extends in a direction at right angles from the neck of the bottle and in position to be gripped and manipulated or to be struck against the edge of a table or bar. Also, as heretofore described, the reinforcing rib of the tongue and one of the ribs between two of the crimps in the rim of the cap intermerge so that the tongue is not weakened at its point of juncture with the rim of the cap, but as a matter of fact is well reinforced at this point and there is no liability of its being bent when manipulated to pry the cap from the bottle.

Having thus described the invention what is claimed as new is:

1. A bottle cap having a crown portion and a locking rim, and a tongue projecting laterally from the rim and having its under side in a plane substantially parallel to the plane of the crown portion, the said tongue being formed with a reinforcing rib extending throughout the entire length thereof and merging into the rim.

2. A bottle cap having a crown portion and a rim formed with an uninterrupted series of crimps, the formation of the crimps resulting in a series of ribs, a tongue projecting laterally from the rim and having its lateral edges merging at their inner ends into the lower edge of the rim at points substantially at the middles of the lower edges of the two adjacent ones of the crimps, the tongue being formed with a

reinforcing rib extending longitudinally thereof and forming a continuation of the rim located between the said two adjacent crimps.

5 3. A bottle cap having a crown portion and a rim formed with an uninterrupted series of crimps, the formation of the crimps resulting in a series of ribs, a tongue projecting laterally from the rim and having 10 its lateral edges merging at the inner ends into the lower edge of the rim at points substantially at the middles of the lower edges of two adjacent ones of the crimps, the under side of the tongue being in a plane with 15 the lower edge of the rim and the tongue being formed with a reinforcing rib extending throughout the entire length thereof and forming a continuation of that one of the ribs which is located between the said two 20 adjacent crimps.

4. A bottle cap having a crown portion and a rim formed with an uninterrupted series of crimps, the formation of the crimps

resulting in a series of ribs, a tongue projecting laterally from the rim and having 25 its lateral edges merging at their inner ends into the lower edge of the rim at points substantially at the middles of the lower edges of two adjacent ones of the crimps, the under side of the tongue being in a plane 30 with the lower edge of the rim and the tongue being formed with a reinforcing rib extending throughout the entire length thereof and forming a continuation of that one of the ribs which is located between the 35 said two adjacent crimps, the said rib upon the tongue decreasing in height and width from the inner end of the tongue to the outer end thereof.

In testimony whereof I affix my signature 40 in presence of two witnesses.
